UNITED STATES PATENT OFFICE

STEPHEN MEZZAPESA, OF BROOKLYN, NEW YORK

SODA WATER FOUNTAIN

Application filed October 7, 1931. Serial No. 567,494.

This invention relates to soda water fountains, and particularly to those for use in connection with the dispensing of edible commodities such as lunches, fruits, cake confectionery and the like.

It is an object of this invention to provide a fountain of the character indicated which will serve to refrigerate such commodities while at the same time contain them for display or dispensing, the interior of the display portion being accessible for the purpose of the introduction and removal of the contents.

In fountains now in general use, storage compartments which are multiplied and employed for storing ice cream, food stuffs, beverages and for other purposes, are associated with pipes for circulating usual liquids for refrigerating purposes and provision is made for insulating the circulating pipes and receptacle. In known constructions, the insulation occupies space which it is the purpose of this invention to utilize for containing the display device for the commodities heretofore mentioned, in order that a fountain may be provided with such display device without increasing the sizes of the usual commercial fountain and without liability of impeding the operations of the dispensers back of the counter or obstructing their view of the customers.

It is a further object of the invention to utilize space formerly occupied by a part of the top of the counter, that is to say, at its inner edge, and the space immediately therethrough containing insulation, as a means for displaying commodities and maintaining them in a cool state, while at the same time maintaining the temperature around the usual syrup jars in the state which is attained in commercial fountains having insulation immediately below the counter.

It is a still further object of the invention to provide novel means for supporting the display case and assembling it in association with the usual riser and the counter slab supported thereby, the case having a construction whereby dual glass windows are supported in spaced relation to each other and

between which pipes may be located for dispensing anti-sweat preparations.

It is a still further object of the invention to produce a soda water dispensing fountain having the aforesaid advantages and objects, the same comprising comparatively few and inexpensive parts which are efficient and satisfactory in use.

With the foregoing and other objects in view, the invention consists in the details of construction, and in the arrangement and combination of parts to be hereinafter more fully set forth and claimed.

In describing the invention in detail, reference will be had to the accompanying drawing forming part of this application, wherein like characters denote corresponding parts in the several views, and in which—

Figure 1 illustrates a view in perspective of a soda water fountain with a device embodying the invention applied thereto;

Figure 2 illustrates an enlarged sectional view through a fragment of a fountain;

Figure 3 illustrates an enlarged sectional view of part of the display container at the outer edge;

Figure 4 illustrates a sectional view of a fragment of the display container at the inner edge; and

Figure 5 illustrates a plan view of a fragment of one of the doors.

In this drawing, 10 denotes the part of the apparatus back of the syrup jars and counter which, in commercial fountains, is usually divided into a plurality of compartments for the storage of ice cream and other food stuffs, the same having openings in the top as at 11 for the deposit of containers 12 provided with covers 13 or, in some instances, the tops of the compartments have doors which can be opened for introducing or removing food-stuffs, but as this part of the fountain may be changed to suit particular requirements, it is believed unnecessary to illustrate or describe the same more in detail.

The structural features of fountains now in general use include insulation located inside of the steel foundation 14 and the lining 15 which extends inwardly to encase the rear of the syrup jars 16. It is the purpose of

the inventor to omit the insulation and to utilize the space formerly occupied by the insulation and its retaining instrumentalities as a location for a commodity holding display cabinet.

In the present embodiment of the invention, the counter slab at its inner edge, instead of extending inwardly beyond the steel foundation and being supported by the insulation, 10 as is the case in many of the commercial fountains, has its inner edge terminating above the said steel foundation in order that it will rest on a flange 17 of a frame member 18, which flange is interposed between the 15 upper edge of the said foundation and the counter slab, the said flange being supported by the said foundation. The flange also extends inwardly, as at 19, beyond the frame member, for a purpose to be presently explained.

In installing the fountain, a riser 20 of the usual type is located in spaced relation to the foundation and the counter slab is secured to it in any appropriate way.

25 It is the purpose of the inventor, as stated, to locate a food holding and display case or cabinet at the rear edge of the counter slab, and the frame member 18 constitutes the outer side wall of the said food container or 30 cabinet which, in the interests of simplicity of description, will be hereinafter referred to as a "cabinet".

The inner side wall 21 comprises an upper frame member 22 extending longitudinally 35 of the fountain and a lower frame member 23 which is parallel therewith but on a lower plane, the said frame member being connected by a plurality of ribs 24 which, with the frame member, form open panels which, 40 however, are closed by doors 25 hinged as at 26 to the lower frame member 23 to swing rearwardly from the top in order that food and the like can be placed in the cabinet or removed therefrom. The lower frame member 45 has a longitudinally extending lug 27 which, with the flange 19 of the frame member 18, constitutes a support for the floor or bottom 28 of the compartment, on which receptacles such as plates or the like for holding food may rest. The lug 27 and flange 19 also support an elongated tray 29 having flanges 30 and 31 which rest on the flange 19 and lug, respectively, and in the space between the tray and the floor 28 one or more 50 refrigerant circulating pipes such as 32 may be located.

The top of the cabinet is transparent in order that its contents may be observed by 60 customers using the counter slab. Under certain conditions, the top may be horizontal, rather than inclined, as it is shown in this illustration, but, in the present embodiment, the bracket 18 has a top flange 33, a channel iron 34 in spaced relation to the flange 33 and 65 thereunder, and an angle iron 35, the flange

36 of which is in spaced relation to the channel iron. Preferably two glass panes 37 and 38 are employed for each section of the cabinet. The outer edge of one glass pane is seated between the flange 33 and the angle iron 34, and the outer edge of the lower glass pane is seated between the channel iron and the flange 36, it being understood that the relation of parts is such that the glass will be held against movement.

In order to prevent sweating of the panes, 70 circulating pipes 39 may be interposed between the panes, and the pipes may be seated in the channel iron, although this is a detail of construction which may be changed to suit particular requirements. The inner edges of the panes 37 and 38 are respectively seated between a flange 40 and a channel iron 41 and between the channel iron 41 and a flange 42 of an angle 43, it being shown that 75 these angle irons and channel irons may be secured to the respective frame members by fastenings 44 such as bolts, screws, rivets or the like.

If desired, the frame member 23 may be 80 provided with a depending flange 45 shaped so that it will form an engagement for the flanges 46 of syrup jars 16 and, of course, suitable brackets or uprights will be provided within the structure on which the frame member 23 or the flange 45 thereof will be supported.

The inventor does not wish to be limited 85 with respect to the lengths of the sections of the floor 28 or the tray 29, as they may be sectional in character for convenience of manipulation in case they are to be removed for repair or replacement.

The fountain has the usual rack 16^b for 90 holding syrup jars, and the space between said jars and the tray 29 is cooled by refrigerant within the said tray. By reason of the provision of the display cabinet and the cooling system associated with it, an attractive exhibit may be made of pastries, cakes and 95 the like, which will be kept in fresh condition by reason of the low temperature which may be maintained in the cabinet. By employing the cabinet for displaying edibles, 100 such as sandwiches and frozen dainties, the customers' appetites may be excited and through this means urged to purchase.

105 By reason of the construction of the device, no auxiliary or extra refrigerating apparatus is necessary, since the refrigerating instrumentality is constructed or built in with the top of the counter and the refrigeration is effective for the syrup jars on the 110 soda fountain. In this way, the cooling means which are used for the jars may be used for the display cabinet and, of course, the refrigerating instrumentality may be coupled or connected with the usual refrigerating systems employed in soda water fountains of 115 this type.

The capacity of the display cabinet may, if desired, be increased by constructing what may be termed a "double deck" therein for holding a large variety of foods and delicacies.

The tray 29 is intended to contain brine which acts as a refrigerant for the contents of the display cabinet.

I claim:

- 10 1. A soda water fountain having a foundation and a lining, the lining terminating below the top of the fountain, a refrigerating instrumentality occupying the space above the lining, a counter slab supported at the 15 outer side of the fountain, and a display cabinet at the inner edge of the counter slab above the refrigerating instrumentality cooled thereby.
- 20 2. In a soda water fountain, a foundation and a lining, the lining terminating below the top of the fountain, a support inside of the lining for holding syrup jars, a refrigerating instrumentality above the lining and effective to cool the syrup jars, and a display 25 cabinet above said refrigerating instrumentality cooled thereby.

3. In a soda water fountain, a foundation including a lining, a support inside the lining for holding syrup jars, a refrigerating instrumentality above the lining effective to cool the syrup jars, and a display cabinet at the outer side of the fountain above said refrigerating instrumentality cooled thereby.

4. In a soda water fountain, a foundation 35 including a lining, a support inside the lining for holding syrup jars, a refrigerating instrumentality above the lining effective to cool the syrup jars, a display cabinet at the outer side of the fountain above said refrigerating instrumentality cooled thereby, and a counter slab supported in front of the fountain approximately on the plane of the display cabinet.

5. In a soda water fountain, a foundation 45 including a lining, a support inside the lining for holding syrup jars, a refrigerating instrumentality above the lining effective to cool the syrup jars, a display cabinet at the outer side of the fountain above said refrigerating instrumentality cooled thereby, said display cabinet comprising an outer frame member and an inner frame member in spaced relation thereto, a floor for the display cabinet supported between the outer and inner frame 55 members, a tray supported by said frame members below the floor, means for refrigerating the space between the bottom of the tray and the floor of the cabinet, a transparent cover for the cabinet, and doors mounted in the inner frame member.

6. In a soda water fountain, a foundation including a lining, a support inside the lining for holding syrup jars, a refrigerating instrumentality above the lining effective to cool 65 the syrup jars, a display cabinet at the outer

side of the fountain above said refrigerating instrumentality cooled thereby, said cabinet comprising outer and inner frame members approximately parallel to each other, means on the inner surfaces of the frame members 70 for supporting panes of glass superimposed and in spaced relation to each other, means on the same frame members for supporting a floor, a tray having flanges supported between the said frame members, and means for refrigerating the space between the bottom of the tray and the floor.

7. A soda water fountain having a counter slab, a display cabinet comprising an outer and an inner frame member in spaced relation to each other, the said outer frame member being supported by a part of the fountain, a counter slab supported by a part of the said frame member, and a transparent cover for the display cabinet supported by the said frame members.

8. A soda water fountain having a counter slab, a display cabinet comprising an outer and an inner frame member in spaced relation to each other, the said outer frame member being supported by a part of the fountain, a counter slab supported by a part of the said frame member, a flange formed at the upper edge of the outer frame member, a channel iron secured to the said frame member in spaced relation to the flange, an angle iron secured to the frame member in spaced relation to the channel iron, a flange at the upper edge of the inner frame member, a channel iron secured to said frame member in spaced relation to the flange, an angle iron secured to the said frame member in spaced relation to the channel iron, and panes of glass having their edges supported between the flanges of the frame members and the channel irons carried thereby and between the channel irons of the said frame members and the angle irons carried thereby, respectively.

9. A soda water fountain having a foundation and a lining, the lining being lower than the foundation, insulation located between the foundation and lining terminating at the top of the lining, a cabinet frame member extending upwardly and having a flange at its lower end resting on the top of the foundation, a counter slab having its inner edge engaging the frame member and supported by the said flange, a cabinet frame member in spaced relation to the first mentioned frame member, means for connecting the upper edges of the frame members together, transparent panes filling the spaces between the frame members and the last mentioned means, means on the frame members for supporting two panes superimposed and spaced apart, means for supplying anti-sweating solutions between the panes, means for supporting a tray and cabinet floor between the first and second named frame members, and means for supplying refrigerant to the tray under the

floor and to the space between the tray and the top of the lining.

10. A soda water fountain having a foundation and a lining, the lining being lower than the foundation, insulation located between the foundation and lining terminating at the top of the lining, a cabinet frame member extending upwardly and having a flange at its lower end resting on the top of the foundation, a counter slab having its inner edge engaging the frame member and supported by the said flange, a cabinet frame member in spaced relation to the first mentioned frame member, means for connecting the upper edges of the frame members together, transparent panes filling the spaces between the frame members and the last mentioned means, means on the frame members for supporting two panes superimposed and spaced apart, means for supplying anti-sweating solutions between the panes, means for supporting a tray and cabinet floor between the first and second named frame members, means for supplying refrigerant to the tray under the floor and to the space between the tray and the top of the lining, and syrup jars supported in proximity to the space above the lining.
